(57) **CLAIM**

The ornamental design for an electrical connector, as shown and described.

DESCRIPTION

FIG. 1 is a top front right perspective view of an electrical connector showing our new design;

FIG. 2 is a top front left perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines shown in the figures are included for the purpose of illustrating portions of the electrical connector and form no part of the claimed design.

1 Claim, 8 Drawing Sheets
